OLIVER I. ROBERTS, OF TOMALES, CALIFORNIA.

CHECK-HOOK.

SPECIFICATION forming part of Letters Patent No. 650,567, dated May 29, 1900.

Application filed June 27, 1899, Serial No. 722,066. (No model.)

To all whom it may concern:

Be it known that I, OLIVER I. ROBERTS, a citizen of the United States, residing at Tomales, in the county of San Francisco and State of California, have invented certain new and useful Improvements in Checkrein-Hooks; and I do hereby declare the following to be a full, clear, and exact description of said invention, such as will enable others skilled in the art to which it most nearly appertains to make, use, and practice the same.

This invention relates to improvements in checkrein-hooks; and it consists in the novel arrangement and construction of the parts hereinafter set forth.

The object of the present invention is to provide a hook to receive the end of the checkrein which will be closed to lock the checkrein in position, but which will not necessitate the drawing of the checkrein farther back than the position in which it normally rests while being placed in the hook.

With these objects in view the invention consists in the various matters hereinafter described and claimed.

In the drawings, Figure 1 is a side elevation of a checkrein-hook constructed in accordance with this invention, the dotted lines being used to indicate the end of the checkrein and the loop with which it is provided. Fig. 2 is a side elevation of the same, the hook being partly cut away to show the construction of the hinged portion of the bridge and the latch for locking the same in position. The interrupted lines herein shown indicate the path of the end of the bridge in being placed in its normal position.

To facilitate the description of the invention, I will assign the letter A to the hook portion. The forward part of this hook is slightly curved and is slotted at its upper end to receive the hinge-wing B' of the bridge B, said wing being pivoted between the side walls of said slot. The rear portion of the hook A is turned upward and extends beyond the height of the forward portion of the hook. The upper end of the rear portion is separated to form a slot to receive the latch C, which is pivoted between the side walls of the slot by means of the pin C'. The latch C when in position fits snugly between the

side walls of the slot in which it is contained and forms, in conjunction with the part of the hook A to which it is applied, a continuous extension above the line of the closed hook 55 or loop, as shown in Fig. 1. In this position it is maintained by the flat spring D, the free end of which rests against the back of the latch, while the fixed end is secured to the hook A. When now these parts, constructed 60 and assembled as herein shown and described, are operated, the bridge B is raised in position shown in Fig. 2 to receive the end of the checkrein E. The bridge in being thrown upward is by reason of its being secured to 65 the forward extension of the hook A also thrown forward and rests in a position practically in line with the forward extension of the hook A. By reason of the bridge B being thus raised, as shown in Fig. 2, in line with 70 the forward extension of the hook A the said bridge may be used as a lever to draw the rein and head back to the desired position, thus facilitating the operation of placing the checkrein. When it is thrown down into its 75 normal position, the bridge B spans across the upper part of the hook A, closing the same. In falling into this position the small hook-like extension B³ strikes against the face of the latch C, and the rest for said extension 80 B³ is formed with a raised shoulder A', which extends in front of the hook B³ when the same is forced into the position shown in Fig. 1, and as therein shown in dotted lines. Immediately the hook B³ passes below the latch C 85 the said latch is thrown, by means of the spring D, over the top of the hook B³, the bottom of the latch C being shaped to conform to the upper surface of the hook B³. In the position as shown in Fig. 1 of the drawings it 90 is impossible to withdraw the hook B³ from the engagement with the shoulder A' until the latch C is raised or withdrawn from on top of the said hook B³. Therefore when in the operation of securing the checkrein the 95 bridge B is thrown down into the closed position, as shown in Fig. 1, all strains which are exerted upon the checkrein, and through it upon the hook A, are prevented from withdrawing the hook B³ from the shoulder A' of 100 the rear portion of the hook A.

When it is desired to withdraw the check-

rein from the hook A, it is first necessary to raise the bridge B. To do this, the latch C must be thrown backward from over the hook B³. It is to accomplish this with ease that I have provided the handle C² for the latch C, which handle extends from the opposite end of the pivot or pin C' from that occupied by the operative end of the latch. This construction facilitates the operation of opening the hook A, for the reason that the direction of the pull on the handle C² and the bridge B are in practically the same direction. The thumb being placed behind the handle C² and the end of the forefinger placed under bridge B, the pull exerted by the thumb upon the handle C² is in a forward direction, the same direction to which the bridge B is to be carried. The latch C being thrown into unlocking position, the bridge B is raised into the position shown in Fig. 2 and the checkrein slipped upward out of the hook A and over the bridge B, releasing the checkrein without necessitating the backward draw of the same, which has heretofore been neces-

sary by reason of the rearward extension of 25 the entrance to the checkrein-hook.

The checkrein-hook herein described is provided with the ordinary screw-pillar A², by means of which it is secured to the saddle of the harness.

Having thus described this invention, what is claimed is—

In a checkrein-hook, a body having forward and rear extensions, said rear extension being slotted, and having a raised shoulder at 35 the bottom of said slot, a bridge pivoted to the forward extension, a hook upon the free end of said bridge adapted to engage over said shoulder, and a latch pivoted to lie in said slot in the rear extension and adapted to lie 40 above said hook when the same engages said raised shoulder; substantially as described.

In testimony whereof I have hereunto set my hand this 17th day of June, 1899.

OLIVER I. ROBERTS.
